SWITCHING SYSTEM FOR ELECTRIC CURRENTS

Axel W. Lundstrom, Drexel Hill, Pa., assignor to
General Electric Company, a corporation of
New York

Application June 11, 1940, Serial No. 339,929.

9 Claims. (Cl. 171—97)

My invention relates to improvements in switching systems for electric currents and more particularly to switching systems for selectively connecting a given circuit to any one of a plurality of sources of electric current but to only one of the sources at a time. The principal object of my invention is to provide an improved switching system such that a given circuit may be connected at any time to only one of a plurality of sources whereby to avoid the necessity for synchronizing operations. This and other objects of my invention will appear in more detail hereinafter.

When ships are docked for any length of time, it may be desirable, for reasons of economy in fuel and reduction of the mechanical operating staff, to connect the ship's lighting load, auxiliaries and the like, to a source on shore. This is particularly the case during repairs, replacements and the like, of a ship's mechanical equipment especially when the ship is in dry dock. Since a single shore source may fail, it is important to have another emergency source upon which to rely. If the sources are alternating current sources, then no two or more of them can be connected to the same circuit without danger unless they are in synchronism. This synchronizing requirement tends to more complicated and costly controls which it is desirable to avoid, if possible, for reasons of economy and simplicity. It is, accordingly, important that a load circuit cannot be connected to two sources at the same time but that it may be selectively connected to the ship's source, a preferred shore source, or an emergency source, as desired, but to only one of these at a time. Equipment for this purpose must be economical in cost, simple to operate, and rugged in structure.

In accordance with my invention, I provide an improved switching arrangement whereby a load circuit may be connected to any one of a plurality of sources of electric current but to only one of these sources at a time through suitable and yet relatively simple and economical interlocking arrangements such that no two switches can be so operated as to be in the closed position at the same time and yet that the circuit may be supplied from any one of the plurality of sources selectively as desired and in case of failure of a particular source.

My invention will be better understood from the following description when considered in connection with the accompanying drawing, and its scope will be pointed out in the appended claims.

In the single figure of the accompanying drawing, which illustrates an embodiment of my invention partly in diagram and partly in perspective, a circuit, indicated by conductors 1, is arranged to be connected to any one of three sources of alternating current, schematically indicated by conductors 2, 3 and 4, but to only one of these sources at a time. For convenience in differentiating the sources 2, 3 and 4, they will hereinafter be designated the normal, preferred and emergency sources. Source 2, for example, may be a ship's source, source 3 a preferred shore source, and source 4 an emergency source, which may also be on shore. For connecting the circuit 1, which may be the ship's load circuit or bus, to the ship's source 2, I provide suitable switching means indicated as a latched closed circuit breaker 5 which is provided with trip and closing coils 6 and 6' respectively, and an "a" auxiliary switch 7. Further, in accordance with my invention, the circuit breaker 5 is provided with suitable means for maintaining it in the open position once that it has been tripped. As shown, this means comprises a coil 8 cooperating with the tripping coil 6 to prevent the reclosing of the circuit breaker. The circuit breaker 5 is of the conventional trip-free type and cannot be momentarily closed, either manually or electrically as long as the closing prevention coil 8 is energized.

For connecting the load circuit 1 to each of the other sources 3 and 4, I provide suitable switching means 9 and 10, respectively, which are schematically illustrated as circuit breakers of the type disclosed in United States Letters Patent 2,047,842 issued July 14, 1936 and assigned to the assignee of this invention. As shown, these circuit breakers 9 and 10 have operating handles 11, which are in the lower position, as shown, when the circuit breaker is open and in the upper position, not shown, when the circuit breaker is closed.

In order to prevent the simultaneous connection of two or more sources to the circuit 1, I provide a control mechanism which includes movable means operative in one position to prevent the closing operation of both of the switches 9 and 10 and in either of two other positions to permit a closing operation of one or the other of these two switches only after effecting an opening operation of the circuit breaker 5. As illustrated, this movable means comprises an operating handle 12, mounted on a shaft 13 one end of which is suitably journaled in a plate 14 secured to the switchboard 15 and the other end

of which is also provided with a suitable bearing, not shown.

For preventing the closing operation of the circuit breakers 9 and 10, I provide, in accordance with my invention, a movable member such as an interlock bar 16 which, in the position shown, prevents the closing movement of the operating handle 11 of each of the circuit breakers 9 and 10. The bar 16 is under the control of the operating handle 12 whose shaft 13 is provided with a slotted crank 17 which engages a pin 18 extending through an opening 19 in the switchboard into the bar 16. This bar may be suitably guided on the switchboard, and for this purpose it may be a channel member, as shown, whose lower flange engages blocks 20 suitably secured to the switchboard 15 and whose upper flange engages suitable resilient shoes 20'.

In order to insure the opening of the circuit breaker 5 before either of the switches 9 or 10 can be closed, the movable means further includes suitable switching means comprising co-operating contacts 21, 22, 23, 24, 25, and 26 which may be operated to the closed and open positions by cam means 27, 28 and 29 suitably disposed on the shaft 13 as, for example, in the manner shown in the drawing. The switching means are so arranged that, upon movement of the handle 12 either to the right or to the left of the position shown to effect movement of the bar 16 so as to permit the closing operation of the switches 10 or 9 respectively, the trip coil 6 of the circuit breaker 5 is energized and also the maintaining coil 8 whereby to effect opening of the circuit breaker and to prevent reclosing thereof as long as the coil 8 is energized. This coil will be energized during the continuation of energization of the source 3 or 4 while the operating handle is in position either to the left of the "off" position shown or to the right of the "off" position. For auxiliary tripping purposes the circuit breaker 5 may have its trip circuit controlled through suitable switching means 30 which may be of any type, examples of which are well known to the art.

Assuming the parts positioned as shown in the drawing and that it is desired to disconnect the load circuit or bus 1 from the source 2 and connect it to the source 3, then the operating handle 12 is turned counter-clockwise or to the left as viewed in the drawing. In consequence of such counter-clockwise rotation of the operating handle, the contacts 21 are closed to complete the circuit of the trip coil 6 from a positive control bus through a conductor 31, the auxiliary switch 7, the trip coil 6, a conductor 32, the contacts 21 and a conductor 33 to a minus control bus. Simultaneously with the closing of the contacts 21 the contacts 23 and 25 are closed to complete the circuit of the closing preventing coil 8 across one phase of the source 3 on the source side of the switch 9 as follows: the center one of the conductors 3, a conductor 34, the contacts 23, a conductor 35, the closing preventing coil 8, a conductor 36, the contacts 25, and a conductor 37 to the right hand conductor 3. In consequence of the energization of the coils 6 and 8, the circuit breaker 5 is opened and prevented from closing as long as the source 3 is energized and the contacts 23 and 25 are closed. Since the interlock bar 16 is now moved to the right to clear the operating handle 11 of the circuit breaker 9, this circuit breaker may be closed to connect the preferred source 3 to the load bus 1. The operation of switching the load bus 1 from

the source 2 to the source 4 is similar to that described except that the operating handle 12 is moved to the right to close contacts 22, 24 and 26 and thereby energize the trip coil 6 and the closing preventing coil 8 which, in this case, is energized from one phase of the source 4 through conductors 38 and 39 in a circuit which will be obvious from the drawing. It will be apparent from the foregoing that any time when the load circuit 1 is connected to either the source 3 or to the source 4 it may be switched from one to the other of these by turning the handle from one extreme position to the other extreme position to move the interlock bar 16 clear of the circuit breaker which it is desired to close to connect the source in question. Any attempt to close the circuit breaker 5 during the movement of the operating handle 12 from one extreme position to the other will not make it possible to effect a closing operation of either of the switches 9 and 10 with the circuit breaker closed since the movement of the operating handle to such position will, as before described, effect the opening of the circuit breaker and keep it open as long as the operating handle remains in the extreme position.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. In combination, a circuit, a plurality of sources of electric current, a first switch for connecting said circuit to one of said sources, and means for connecting said circuit to another of said sources only when said first switch is open comprising a switch for said other source and means movable to one position for preventing a closing operation of said other switch and movable to another position for effecting an opening operation of said first switch and subsequently permitting operation of said other switch.

2. In combination, a circuit, a plurality of sources of electric current, a first switch for connecting said circuit to one of said sources, means for connecting said circuit to another of said sources only when said first switch is open comprising a switch for said other source and means movable to one position for preventing a closing operation of said other switch and movable to another position for effecting an opening of said first switch and subsequently permitting operation of said other switch, and means for preventing the closing of said first switch while said movable means is in said other position.

3. In combination, a load circuit, three sources of electric current, a circuit breaker for connecting said load circuit to one of said sources, and means for tripping said circuit breaker and for connecting said load circuit to either of the other two sources only when said circuit breaker is open comprising two switches and a control mechanism operative in one position mechanically to interlock both of said switches in the circuit opening position and to either of two other positions to effect the energization of said tripping means and to remove the interlock from one of said switches.

4. In combination, a circuit, three sources of electric current, a first switch for connecting said

circuit to one of said sources, means for connecting said circuit to either of the remaining two sources only when said first switch is open comprising a switch for each remaining source and a control mechanism including movable means operative in one position to prevent a closing operation of both of the remaining source switches and in other positions to permit operation of only one of said remaining source switches only after effecting an opening of said first switch; and means for maintaining said first switch open while said movable means is in any one of said other positions.

5. In combination, a load circuit, three sources of electric current, a latched closed circuit breaker for connecting said load circuit to one of said sources, tripping means for releasing said latched closed circuit breaker to effect the opening thereof, means for subsequently maintaining said tripping means in the tripping position, and means for connecting said load circuit to either of the other two sources only when said circuit breaker is open comprising two switches and a control mechanism including a movable member operative in one position mechanically to interlock both of said switches in the circuit opening position and to either of two other positions to effect the energization of said tripping means and the operation of said maintaining means and to remove the interlock from one of said switches.

6. In combination, a load circuit, three sources of electric current, a circuit breaker for connecting said load circuit to one of said sources, electromagnetic means for effecting the opening of said circuit breaker and subsequently preventing the closing thereof, and means for effecting the energization of said electromagnetic means and for connecting said load circuit to either of the other two sources only when said circuit breaker is open comprising two switches and a control mechanism including a movable member operative in one position mechanically to interlock both of said switches in the circuit opening position and to either of two other positions to effect

the energization of said electromagnetic means and to remove the interlock from one of said switches.

7. In combination, a load circuit, three sources of electric current, a circuit breaker for connecting said load circuit to one of said sources, and means for effecting the opening of said circuit breaker and maintaining it open and subsequently connecting said load circuit to either of the other two sources comprising two switches and a control mechanism including a movable member operative in one position to prevent a circuit closing action of both of said two switches and movable from said one position to either of two other positions to effect the opening of said circuit breaker and to maintain it open while in such other position and to permit the closing of one of said two switches.

8. In combination, a circuit, three sources of electric current, a first switch for connecting said circuit to one of said sources, and means for connecting said circuit to either of the remaining two sources only when said first switch is open comprising a switch for each remaining source and a control mechanism including movable means operative in one position to prevent a closing operation of both of the remaining source switches and in other positions to permit operation of only one of said remaining source switches only after effecting an opening of said first switch.

9. In combination, a circuit, three sources of electric current, a first switch for connecting said circuit to one of said sources, and means for connecting said circuit to either of the other two sources only when said first switch is open comprising two switches, and a control mechanism including movable means operative in one position to prevent a closing operation of both of said two switches and in either of two other positions to permit a closing operation of one or the other of said two switches only after effecting an opening operation of said first switch.
